CLAIM

I claim the ornamental design for a noise reducing water resistant headwear cap, as shown and described.

DESCRIPTION

FIG. 1 is a perspective view of a noise reducing water resistant headwear cap, in accordance with the present invention;

FIG. 2 is a front perspective view of the invention shown in FIG. 1 thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view of the noise reducing water resistant headwear cap shown in FIGS. 1-7 as worn by an individual in accordance with the present invention.

The partial human figure depicted by broken lines represents environmental structure that forms no part of the claimed design. The broken lines that encircle the interior portion of the headwear cap are boundary lines that form no part of the claimed design.
